UNITED STATES PATENT OFFICE.

JOHN McCULLOCH, OF LOSTOCK-GRALAM, ENGLAND.

RAILWAY-SLEEPER.

1,041,134.

Specification of Letters Patent.

Patented Oct. 15, 1912.

Application filed March 20, 1911. Serial No. 615,525.

To all whom it may concern:

Be it known that I, JOHN McCULLOCH, a British subject, residing at Lostock-Gralam, county of Chester, England, have invented 5 certain new and useful Improvements in Railway-Sleepers, of which the following is a specification.

This invention relates to improvements in railway sleepers.

10 It consists of a railway sleeper composed of wood or cork saw dust or other fiber, magnesium oxid and farina incorporated together, with a solution of chlorid of magnesium or hydrochloric acid, or lilienna as 15 a binding material the whole being compressed under intense pressure and provided with corner pieces to prevent the sleeper from splitting, and reinforcing members embedded therein.

20 The invention will be described with reference to the accompanying drawings.

Figure 1 is a perspective view of part of the sleeper showing the corner pieces in position. Fig. 2 is a perspective view of the 25 corner pieces with the tie rods attached. Fig. 3 is a side view of the sleeper partly in section. Fig. 4 is a plan of the sleeper. Fig. 5 is a side view of a modification. Fig. 6 a detail view partly in section showing 30 in plan the holes for receiving the dogs fitted with metal bushes. Fig. 7 is a section of same.

The sleeper A is composed of wood or cork saw dust or other fiber, magnesium 35 oxid and farina incorporated together with a solution of chlorid of magnesium or hydrochloric acid and compressed under an intense pressure.

The following proportion of the mixture 40 is found to give good results:—Wood saw dust 30%, magnesium oxid 25%, farina 10%, magnesium chlorid 35%.

Metal corner pieces B of the shape shown 45 are placed at each corner of the sleeper to prevent it splitting and to hold in position the cross or tie bars b. The metal corner pieces B and the tie rods b are placed in position before the composition forming the sleeper is compressed so that on the 50 position being compressed these are firmly

embedded in the sleeper. The corner pieces B are provided with holes b' through which the ends of the tie bars b pass and are then bent over into hook shape to hold them firmly in position.

55

Grooves c are formed in the top surface of the sleeper for the rails to rest in and to prevent the rails spreading out. The rails are held in position by square dogs driven into the round holes d. Or the holes 60 d may be fitted with metal bushes d' as shown in Figs. 6 and 7 to prevent the dogs from splitting the material.

Instead of tie bars strips of wire netting b² may be stretched across from the corner 65 pieces as shown in Fig. 5.

What I claim as my invention and desire to protect by Letters Patent is:—

1. The combination with a composition tie, of a metal end plate, said plate being 70 bent at right angles along a longitudinal central line, one-half of the plate engaging a surface face of the tie, and the other half of the plate over-lapping a portion of the end of the tie, said plate having inwardly 75 extending flanges along its opposite sides, said flanges being embedded in the tie, and being also at right angles to each other, said plate extending transversely across the tie from one side to the other.

80

2. The combination with a composite tie, of angled transversely extending end plates fitting respectively upper and lower edges of the tie, the said marginal portions of said plates being bent at an angle and embedded 85 in the tie, and metal connecting rods extending longitudinally through the tie, said rods crossing each other in the center of the tie, each of said rods being secured at one end to a plate fitted upon a lower edge of the 90 tie, and secured at the opposite end to a plate fitted upon an upper edge of the tie.

In testimony whereof I have hereunto set my hand in presence of two subscribing witnesses.

JOHN McCULLOCH.

Witnesses:

GEO. H. O'BRIEN,
HARRY BARNFATHER.
